UNITED STATES PATENT OFFICE.

JAMES S. GIPSON, OF FORT STOCKTON, TEXAS.

FUEL-OIL BURNER.

1,224,372.

Specification of Letters Patent.

Patented May 1, 1917.

Application filed August 14, 1916. Serial No. 114,884.

To all whom it may concern:

Be it known that I, JAMES S. GIPSON, a citizen of the United States, residing at Fort Stockton, in the county of Pecos and 5 State of Texas, have invented certain new and useful Improvements in Fuel-Oil Burners; and I do declare the following to be a full, clear, and exact description of the invention, such as will enable others skilled 10 in the art to which it appertains to make and use the same.

This invention relates to improvements in fuel oil burners or heaters which are adapted to be placed in the fire box of any 15 ordinary type of stove, particularly cook stoves.

The primary object of the invention is to provide a device of this character which while being simply constructed will be very 20 efficient in operation.

An additional object is to provide a device formed of two heaters, each of which may be operated independently of the other, one being used for heating the oven, while 25 the other is used for heating the parts of the stove above the fire box.

Still another object is to provide air inlet means whereby air is supplied to the burner openings in both parts of the device.

With these and many other objects in 30 view, my invention resides in the features of construction shown in the accompanying drawings which will be later described and claimed.

In these drawings:

Figure 1 represents a longitudinal sectional view through the fire box of a stove with my improved heater disposed therein, the latter being in side elevation;

Figs. 2 and 3 are horizontal sections taken respectively on the planes of the lines 2—2 and 3—3 of Fig. 1;

Figs. 4 and 5 are vertical transverse sections on the planes of the lines 4—4 and 45 5—5 of Fig. 2;

Fig. 6 is a detail section on the plane of the line 6—6 of Fig. 3;

Fig. 7 is a transverse section on the line 7—7 of Fig. 2; and

Fig. 8 is a detail sectional view through 50 a portion of the tubing which comprises the pipes of the heater.

Referring more particularly to the drawings the reference character F represents 55 the fire box of a stove S, the fire box being provided with the usual grate G upon which

my improved heater is designed to rest. Before the heater is placed within the fire box, however, a sheet of asbestos 1 is disposed upon a plate 1' so as to exclude air 60 from the fire box and also to form a pan upon which fuel oil is disposed and lighted in order to generate gas within the heater preliminary to starting the same.

This heater comprises a burner section 2 65 and a vaporizing section 3, the pipes of each section being disposed in substantially parallel spaced apart planes, the lower or burner section having a plurality of sets of openings therein through which the gas generated in the upper section is liberated.

The heater is also formed in two parts 4 and 5, either of which may be operated independently of the other, and each of which consists of a single piece of tubing of suitable diameter, one end portion containing burner openings while the other is connected to the source of supply of the fuel oil. The part 4 will be termed a heater proper and has one end extended through the front 75 of the fire box, which is closed in a suitable manner, and is connected to any preferred form of cut-off valve 6 through which the fuel oil from the tank (not shown) passes on its way to the burner. The oil before 80 reaching the valve 6 passes through the pipe 7. The opposite end portion of this part of the heater is bent upon itself to form a loop 8, the arms 9 and 10 of which are disposed substantially parallel and in 85 the same horizontal plane as shown in Figs. 3 and 4. The base of this loop is shown disposed at the rear end of the fire box, and the free end thereof is extended upwardly as 90 at 11, then continued laterally toward the rear of the fire box in a plane substantially parallel to that of the loop 8, and then bent upon itself to form an additional loop 12, the arms 13 and 14 of which are disposed 95 substantially over the arms 9 and 10 of the loop 8. Both the arms 13 and 14 are disposed in the same horizontal plane which is parallel with that of the loop 8, and they form a part of the vaporizing section 3, the rest of which will be later described. The 100 free end of the arm 14 of the loop 12 is next bent downwardly and then continued laterally toward the rear of the fire box parallel to and substantially in the plane of the arms 9 and 10 of the loop 8 in order 105 to form a burner 15 in which a plurality of sets of burner openings 16 are formed. This

110

portion 15 is preferably arranged directly between the arms 9 and 10 and has its openings 16 positioned upwardly so that the flames therefrom extend to the vaporizing section directly above. 5 The other part 5 which is termed the oven heater, also, has one end extended through an opening in the front of the fire box of the stove connected to a suitable cut-off valve 17 through which the fuel oil passes 10 from the pipe 7. The opposite end portion is bent upon itself to form a loop 18, the arm 19 of which being the supply pipe or portion of the member 5 which is connected to the valve 17, and the other arm 20 is positioned between and parallel to the arms 13 and 14 of the loop 12 as shown in Figs. 2 and 4. The inner portion of the arm 19 is disposed adjacent the arm 10. The free end of the arm 20 is bent downwardly and laterally to form the burner portion 21 which is arranged parallel to the arms of the other loops and adjacent the arms 10 and 19. The burner openings 22 of this portion 21 are inclined so as to throw the flames which issue therefrom toward the inner or oven wall of the fire box F in order to quickly and thoroughly heat the oven. 25

From this description it will be seen that the burner section includes the arms 9, 10 and 15 of the part 4 and the arms 19 and 21 of the part 5, and that the vaporizing section comprises the arms 13 and 14 of the loop 12 and the arm 20 of the part 5. These two parts are effectively held in co-operative position with respect to each other by means of the tie straps 23 which surround the arms 13, 14 and 20. The pipe 7 which connects the valves 6 and 17 also aids in spacing the outer end portions of the parts 4 and 5 and holds them in position. 40

In the present device I have shown two sets of burner openings 16, one being adjacent each end of the arm 15. Surrounding the supply pipes of the burners which are formed by the arms 9 and 19, are air inlet tubes 24 and 25 respectively, these tubes being extended through openings in the front of the fire box so as to permit air to enter the interior of the latter. The inner ends of the tubes terminate adjacent the sets of openings 16, the tube 24 terminating adjacent the innermost set of openings, while the tube 25 stops near the outermost set, thus supplying the needed amount of air to the gas directly at the point of discharge. Fingers or spiders 26 are arranged within these two tubes 24 and 25 in order to space the same from the supply pipe. It will also be noted that the tube 25 terminates adjacent the openings 22 in the oven burner portion 21 so that air is also supplied thereto. 55

In order to spread the flames which issue 60 from the openings 16 and direct them upon

the arms 13 and 14 of the vaporizing section, I provide the deflecting members 27 which are in the form of asbestos sleeves bound by copper rings 28 and are disposed upon the arm 20. These deflectors are slideable upon the arm 20 so as to permit them to be disposed over the openings 16 or not as desired. By this arrangement the intense heat from the burner section is directed upon all parts of the vaporizing section so as to evenly heat the same. 70 75

All parts of the tubing which comprise the heater proper and also the burner heater are filled with a plurality of strands of wire 29 as shown in the figures on the second sheet of drawings. This construction permits the fuel oil within the tube to be very quickly vaporized when heat is applied thereto, since only a small quantity of oil can be contained therein at one time. 80 85

With the parts disposed in the fire box of the stove S as hereinbefore described, the burners are prepared for lighting by pouring a quantity of fuel oil upon the asbestos pan 1 and igniting the same, thus heating the parts of the burner and vaporizing the oil therein. When this oil has become vaporized, and supposing it is desired to light both parts of the device which include the burner openings 16 and 22, both the valves 6 and 17 are opened to permit the fuel oil to flow from the tank, and the gas is ignited. The flames from the openings 16 will cause the oil which is continuously flowing from the tank through the valves 6 and 17 to become vaporized so that it may flow from the burner openings in the form of gas, the flames from the openings 22 also aiding in this vaporizing operation to a certain extent. Where it is only desired to heat articles upon the top of the stove over the fire box, the valve 17 is cut off so as to stop the flow of oil to the oven heater. The formation of gas within the vaporizing section 3 continues, thereby supplying gas to the burner openings 16. When only the oven heater is desired, the other valve is cut off. It is obvious that it is unnecessary to start the heater pipe by lighting both parts thereof, either one may be started in the same manner independently of the other. 90 100 105 110 115

While the heater is shown disposed within the fire box of a cook stove and it is primarily designed for use in such, it is evident that with slight changes it may be used in a stove designed only for heating purposes. In such a case the oven burner could be done away with or so arranged that its openings are directed upon the vaporizing section. 120 125

I claim:

1. In a device of the class described, a heater adapted to be disposed in the fire box of a stove, comprising a burner section 130

and a vaporizing section, the first section having a plurality of sets of burner openings, a plurality of sliding deflectors movable on the vaporizing section and adapted 5 to be disposed over said openings, each of said deflectors consisting of a heat resisting sleeve surrounding said vaporizing section, and metallic bands surrounding said sleeves.

2. The combination with the fire-box of a 10 stove, of a two-part heater therein, each part of said heater having burner openings, a supply pipe for each of said parts, tapered cylindrical air inlet pipes extending through one wall of said fire-box, one of said pipes 15 surrounding each of said supply pipes, and fingers projecting inwardly from said inlet pipes into engagement with said supply pipes to space the former therefrom.

3. A device of the class described comprising 20 a burner formed from a single piece of tubing, one end being connected to the source of supply, the opposite end portion being bent upon itself to form a loop, the arms thereof being substantially parallel 25 and in the same horizontal plane, the free end portion being bent upwardly, then continued laterally in a plane parallel to the first mentioned plane and bent upon itself to provide an additional loop, the free end 30 thereof being bent downwardly and laterally and disposed between the arms of the first mentioned loop, said last mentioned end having burner openings, and an air inlet pipe for supplying air to said burner 35 openings.

4. A device of the class described comprising 40 a burner formed from a single piece of tubing, one end being connected to the source of supply, the opposite end portion being bent upon itself to form a loop, the arms thereof being substantially parallel 45 and in the same horizontal plane, the free end portion being bent upwardly, then continued laterally in a plane parallel to the first mentioned plane and bent upon itself

to provide an additional loop, the free end thereof being bent downwardly and laterally and disposed between the arms of the first mentioned loop, said last mentioned end having burner openings, an air inlet pipe, a 50 second burner formed from a single tube having one end connected to a source of supply, the other end portion being disposed between the last mentioned loop and over said burner openings, and deflectors on 55 the last named portion of the second burner.

5. A device of the class described comprising 60 a two-part burner, one part being formed from a single piece of tubing, one end being connected to the source of supply, 65 the opposite end portion being bent upon itself to form a loop, the arms thereof being substantially parallel and in the same horizontal plane, the free end portion being bent upwardly, then continued laterally in a 70 plane parallel to the first mentioned plane and bent upon itself to provide an additional loop, the free end thereof being bent downwardly and laterally and disposed between the arms of the first mentioned loop, 75 said last mentioned end having burner openings, and a second part formed from a single piece of tubing having one end connected to the source of supply, the opposite end portion being bent into the form of a 80 loop, one arm thereof being adjacent one arm of the first mentioned loop of the other part, the other arm being disposed between the arms of the other loop of the first mentioned part, the free end of said loop being then bent between the arms thereof and having burner openings therein.

In testimony whereof I have hereunto set my hand in the presence of two subscribing witnesses.

JAMES S. GIPSON.
